UNITED STATES PATENT OFFICE.

HENRY J. PAPIN, OF GRAND RAPIDS, MICHIGAN.

GRIP.

Application filed June 28, 1926. Serial No. 118,989.

My invention relates to grips and more particularly to grips for golf clubs and the like. In the playing of certain games wherein implements or clubs are necessary for hitting and driving it is essential, in securing the best results, to hold the striking implement or club in a correct manner. In golf, for instance, it is absolutely essential that the club be held or gripped with the hands 10 of the player in such a manner that at the moment the face of the club or driving implement comes in contact with the ball that it would be in proper position and alignment with the ball and be firmly held in the hands 15 so that the ball will be driven in a straight line. In order to obtain this result, the manufacturers of clubs mark the faces or striking part of said clubs in such a manner and along certain pre-determined angles as 20 to obtain the results desired as to distance, elevation, etc.; but with all the improvements now in use the best results now depend largely upon the ability of the player to hold or grip the club handle or shaft in 25 the proper manner. To correctly hold the various golf clubs, the grip for rigidity and stability of the club should rest largely within the left hand and the alignment and direction rests largely within the right hand. 30 One object of the present invention is to provide an improved grip of novel construction whereby the proper position of the hands is attained without special effort on the part of the player and to provide a grip 35 which cannot conveniently be held in any except the proper manner.

With the above and other objects in view this invention has particular relation to certain novel features of construction and use, 40 an example of which is described in this specification and illustrated in the accompanying drawings, wherein:—

Figure 1 shows a side elevation of the improved type of grip shown on the handle of 45 a golf club.

Figure 2 shows a front elevation of the improved grip, and

Figure 3 shows a front view of the grip, as grasped by the hands of the player.

Referring now more particularly to the drawings, wherein like numerals of reference designate similar parts in each of the figures the numeral 1 designates the handle of a golf club, and the numeral 2 designates the grip 50 as a whole. This grip may be termed a double type of grip with grooves 3, 4, 5 and

6 to receive the fingers of the right hand and the grooves 7, 8, 9 and 10 to receive the fingers of the left hand. As clearly shown in Figures 1 and 2 these respective grooves are 60 disposed diagonally relative to the axis of the grip and in different directions, that is, the right hand grooves are inclined in different directions with respect to the inclination of the left hand grooves and these right 65 and left hand grooves have correspondingly inclined ribs, as 11 and 12, respectively between them, thus forming secure gripping means preventing the slipping of the grip in the hands of the player, as well as making 70 a more powerful drive possible.

The respective right and left hand grooves are inclined to correspond to the inclination of the respective right and left hand fingers, of the player, when grasped about the grip 75 2, and the inclination is such that when the fingers are properly located in their respective grooves the striking face of the club will be held in proper angular relation with the desired line of travel of the ball at the 80 moment such face comes in contact with the ball and this without any special effort, or technical knowledge, on the part of the player.

In the illustration shown there is an oval 85 rib 14 disposed substantially midway between the adjacent grooves 6 and 10, which if desired enables the player to use the interlocking hand grip, as is common practice 90 with some players.

There is also an extra groove, as 17, for the right hand, for players desiring a lower grip.

It will be understood that this improved grip can either be made or carved upon the 95 permanent handle of the club, or can be made separate, of rubber, or other like substance, and tubular and fitted over the reduced end 15, of the handle, and fastened thereto as by means of rivets 16. 100

While this improved grip is primarily intended for use in connection with golf clubs and is intended to enable a player to hold the club in exactly the right manner, the grip may be utilized in connection with other 105 types of clubs to be used in other games, or any other purposes, and will be equally effective.

What I claim is:—

1. A grip for golf clubs and the like having two series of grooves, therearound with intervening ribs, said grooves being of uni- 110

form contour and inclined with respect to the axis of the club handle, the grooves of one series being inclined with respect to the axis of the club handle, in a direction the 5 opposite of the direction of inclination of the grooves of the other series, to correspond with normal positions of the fingers of the right and left hand in grasping the club.

2. A grip for a hand implement having 10 two series of grooves, one series being for the right hand and the other series being of uniform contour and for the left hand, said grooves being inclined relative to the longitudinal axis of the handle, and in opposite 15 directions.

3. A grip for a hand implement having two series of grooves inclined with respect to the longitudinal axis of the implement and disposed to correspond to the positions 20 of, and to receive the fingers, of the right and left hands, respectively, of the user, and an oval rib around the grip between said series of grooves.

4. A grip for a hand implement, such as 25 a golf club, having two series of grooves inclined with respect to the longitudinal axis of the implement, the grooves of one series

being inclined in a direction the opposite of the direction of inclination of the grooves of the other series, the grooves of each series 30 being substantially of uniform contour and extending all the way around the grip, said series of grooves being spaced apart and an oval rib disposed around the grip substantially midway between the series of grooves. 35

5. The combination with a golf club having a handle whose outer end is reduced, of a tubular grip fitted over said reduced end, means for securing the grip to the reduced end of the handle, the outer surface of said 40 grip being provided with two series of grooves, the grooves of each series being inclined in opposite directions with respect to the axis of the handle to correspond with the normal positions of the fingers of the right and left hands in grasping the club, the 45 grooves of each series being substantially of uniform contour and extending all the way around the grip, said series of grooves being spaced apart and a rib disposed substantially midway between the series of grooves, the exterior of said rib being convex. 50
